UNITED STATES PATENT OFFICE.

FALLIE COOK, OF COMMERCE, OKLAHOMA.

BED REGULATOR AND CHATTER FOR JIGS.

Application filed October 11, 1926. Serial No. 140,974.

This invention relates to a novel apparatus for separating strata of ore, ore bearing material and waste material passing over an ore separating jig, and more particularly to a chatter and bed regulator for jigs.

The principal object of my invention is to provide novel means for separating from waste material and conducting away by different channels clean ore and ore bearing chats in a more efficient manner than has been possible with the devices heretofore used.

An important object of my invention is to provide a novel combination between the grate or bed of a pulsating jig and a separating device whereby an eddy is produced which tends to move the separated material more readily through the separating device.

A further object of my invention is to provide means whereby a constant bed of ore is maintained on the jig grate.

In the accompanying drawings I have shown a preferred embodiment of my invention. In this showing,

25 Figure 1 is a fragmentary plan view,

Figure 2 is a section on line 2—2 of Figure 1,

Figure 3 is a side elevation with the front vertical plate broken away,

30 Figure 4 is a view on line 4—4 of Figure 3,

Figure 5 is an end elevation of the hoppers,

Figure 6 is a section on line 6—6 of Figure 3, and,

Figure 7 is a section on line 7—7 of Figure 3.

Referring to Figures 1 and 2 of the accompanying drawings, reference numeral 10 indicates generally a conventional type of pulsating jig consisting of a plurality of compartments each of which is provided with a hutch 11 having inclined bottom plates or baffles 12, a reciprocating plunger 13, and a plunger rod 14 suitably connected to an eccentric 15 mounted on the shaft 16, whereby the plunger 13 is caused to reciprocate upon the rotation of the shaft 16 in an obvious manner. The shaft 16 is suitably journaled as at 17 on stationary portions of the jig 10. At one side of the hutch 11 near the upper portion thereof is provided the usual grate 18 (Figure 2) over which the crushed material from an ore crusher is adapted to pass in the usual manner. The

grate 18 is suitably mounted on supports 19. Strata separating devices generally indicated by the numeral 20 are mounted on the grate in each compartment of the jig and are obliquely disposed with relation thereto 60 for a purpose hereinafter to be described.

The crushed material from the crushing mill is adapted to pass over the grates of the jig in a direction indicated by the arrows in Figure 1 and water is caused to pulsate 65 through the jig bed or grate 18 in a known manner to cause the crushed material to form strata of clean ore, chats or ore bearing material, and gangue or waste material by virtue of the difference in specific gravity 70 of the various materials. As is conventional, each successive compartment of the jig is at a lower level than the next preceding compartment.

It has been the practice to provide means 75 for separating the strata of materials passing over the jig grate but the devices which have been employed up to the present time have had the disadvantage that a considerable amount of the chats would be "pulled" 80 or carried with the ore and an excessive amount of the gangue or waste material would be carried off with the chats. To overcome this serious disadvantage I have provided a novel construction which will 85 separate the strata in a more satisfactory manner than has heretofore been possible. I have found that my chatter will "pull" less waste by 75% than any of the chatters 90 with which I am familiar.

My chatter or separating device 20 comprises spaced horizontally disposed plates 21 and 22 which form an opening 23 therebetween. The plates 21 and 22 are provided with sharp forward edges. The opening 23 between the plates 21 and 22 communicates with a channel or chat runway 24 the bottom of which is open to the action of the pulsating water through the grate substantially throughout the length thereof. 95 The horizontal plate 21 is secured to or forms a part of the substantially vertical supporting plate 25 which also forms one side of the chat runway 24. Suitably secured below the plate 22 and rearwardly of the front edge thereof is a substantially vertical plate 26 provided with a plurality of openings 27 in the face thereof. The openings 27 communicate with a channel or ore runway 28 one side of which is formed 100

110

by the substantially vertical plate 29 which supports the horizontal plate 22 and the bottom of which is closed substantially throughout its length but is provided with an opening 30 near its forward end. The plate 26 is provided with a rearwardly formed baffle 31 arranged below the opening 27 and extending over the opening 30 in the bottom of the runway 28. The baffle 31 serves the purpose of deflecting the pulsating water coming through the opening 30 rearwardly to prevent the water from moving over the opening 27 near the forward end of the chatter and hindering the ready passage of the ore through the opening 27. The runways 24 and 28 communicate at one end thereof with suitable hoppers 32 and 33 which are provided with outlet openings 34 and 35 which communicate with suitable openings 36 in the sides of the jig. The openings 34 and 35 are provided with control gates 37 to regulate the rate of flow of the separated materials.

In the operation of the device the crushed material passing over the jig grate forms strata of ore, chats and gangue by virtue of the pulsations of water through the jig grate. These materials in strata are encountered in their movement across the bed of the jig by my improved separating device. The horizontal plate 21 is designed to enter at the line of demarkation between the waste material and the ore bearing chats. The waste material passes over the plate 21 and the chats enter the opening 23 between the plates 21 and 22, the latter being designed to enter the stratified materials at the line of demarkation between the chats and the ore. The chats passing into the opening 23 enter the chat runway 24 and pass therealong to the hopper 32 and through the opening 34 and one of the openings 36 from which point they are conducted away for further working over to extract the ore which they contain. A portion of the stratum of ore is caused to enter through the openings 27 into the runway 28 along which it passes into the hopper 31 and out of the outlet opening 35 and one of the openings 36 in the side wall of the jig.

Because of the inclined relation of the separating device 20 to the moving current of crushed materials an eddy is set up which moves in a direction from the forward end of the device toward the hopper end with the result that the chats and ore passing into their respective runways are caused to move more readily along the runways to the hoppers. Since the chats do not move readily over a plane surface, the bottom of the chat runway is open throughout its length to the pulsations of water through the grate to assist the movement of the chats along the runway 24. However, the clean ore moves very readily over a surface and, hence

the bottom of the ore runway 28 is closed throughout the greater portion of its length to prevent any substantial amount of the ore passing through the grate 18 into the bottom of the hutch 11. Only a small opening 30 is provided in the bottom of the runway 28 to admit the pulsating water into the runway to assist in moving the ore therealong.

In order to provide a constant bed of ore on the grate so that the ore moving along the jig will more readily pass thereover the openings 27 are spaced from the bottom of the vertical plate 26 so that the lower portion of the plate 26 forms a dam to prevent the lower portion of the stratum of ore from moving along.

From the foregoing description it will be apparent that I have provided an extremely simple device for separating the various strata of crushed material passing over the bed of a jig. This device is susceptible of ready application to the existing types of jigs in operation and this feature is also an important object of my invention.

While I have described in detail the preferred embodiment of my invention it is to be understood that the details of construction such as size, shape and arrangement of parts may be variously modified without departing from the spirit of the invention or the scope of the subjoined claims.

I claim:

1. The combination with the bed of a pulsating jig, of means arranged on and obliquely of said bed for separating strata of ore, ore bearing material, and waste material passing thereover and separate channels for conducting away the separated ore and ore bearing material, one of said channels being closed at the bottom thereof substantially throughout its length but being provided with an opening near the forward end thereof.

2. The combination with the bed of a pulsating jig, of means arranged on said bed for separating strata of ore, ore bearing material, and waste material passing thereover and separate channels for conducting away the separated ore and ore bearing material, one of said channels being open at the bottom thereof substantially throughout its length, the bottom of the other of said channels being closed throughout the greater portion of its length but being provided with an opening near the forward end thereof.

3. A device of the character described comprising spaced horizontally arranged plates forming an opening therebetween, means forming a channel communicating with said opening, and a substantially vertically disposed plate arranged beneath the lower of said horizontal plates, said vertical plate being provided with an opening

throughout a portion of its length, said last mentioned opening being spaced from the bottom edge of said vertical plate.

4. A device of the character described comprising spaced horizontally arranged plates forming an opening therebetween, means forming a channel communicating with said opening, and a substantially vertically disposed plate arranged beneath the lower of said horizontal plates, said vertical plate being provided with openings throughout a portion of its length, said last mentioned openings being spaced from the bottom edge of said vertical plate, said vertical plate being arranged rearwardly of the front edge of the lower of said spaced horizontal plates.

5. A device of the character described comprising spaced horizontally arranged plates forming an opening therebetween, means forming a channel communicating with said opening, a substantially vertically disposed plate arranged beneath the lower of said horizontal plates, said vertical plate being provided with openings throughout a portion of its length, said last mentioned openings being spaced from the bottom edge of said vertical plate, and means providing a channel communicating with the openings in said vertical plate.

6. A device of the character described comprising spaced horizontally arranged plates forming an opening therebetween, means forming a channel communicating with said opening, and a substantially vertically disposed plate arranged beneath the lower of said horizontal plates, said vertical plate being provided with openings throughout a portion of its length, said last mentioned openings being spaced from the bottom edge of said vertical plate, said channel being opened at the bottom thereof substantially throughout its length.

7. A device of the character described comprising spaced horizontally arranged plates forming an opening therebetween, means forming a channel communicating with said opening, and a substantially vertically disposed plate arranged beneath the lower of said horizontal plates, said vertical plate being provided with openings throughout a portion of its length, said last mentioned openings being spaced from the bottom edge of said vertical plate, said vertical plate being arranged rearwardly of the edge of the lower of said spaced horizontal plates, means forming a channel communicating with the openings in said vertical plate, the bottom of said last mentioned channel being closed throughout the greater portion of its length but being provided with an opening at one end thereof.

8. A device of the character described comprising spaced horizontally arranged plates forming an opening therebetween,

means forming a channel communicating with said opening, and a substantially vertically disposed plate arranged beneath the lower of said horizontal plates, said vertical plate being provided with an opening throughout a portion of its length, said last mentioned opening being spaced from the bottom edge of said vertical plate, said horizontal plates being provided with sharp edges.

9. A device of the character described comprising spaced horizontally arranged plates, a substantially vertically disposed plate arranged beneath the lower of said horizontal plates, said vertical plate being provided with openings throughout a portion of its length and spaced from the bottom edge of said vertical plate, and means forming a channel communicating with said openings, said vertical plate being arranged rearwardly of the edge of the lower of said spaced horizontal plates, the bottom of said channel being closed throughout the greater portion of its length but being provided with an opening at one end thereof, said vertical plate being provided with a rearwardly formed baffle adjacent the lower part of one of the openings in said vertical plate and extending over the opening in the bottom of said channel.

10. A device of the character described comprising spaced horizontally arranged plates forming an opening therebetween, means forming a channel communicating with said opening, a substantially vertically disposed plate arranged beneath the lower of said horizontal plates, said vertical plate being provided with openings throughout a portion of its length, said last mentioned openings being spaced from the bottom edge of said vertical plate, said vertical plate being arranged rearwardly of the front edge of the lower of said spaced horizontal plates, and a hopper communicating with said channel.

11. A device of the character described comprising spaced horizontally arranged plates forming an opening therebetween, means forming a channel communicating with said opening, a substantially vertically disposed plate arranged beneath the lower of said horizontal plates, said vertical plate being provided with openings throughout a portion of its length, said last mentioned openings being spaced from the bottom edge of said vertical plate, said vertical plate being arranged rearwardly of the front edge of the lower of said spaced horizontal plates, a second channel communicating with the openings in said vertical plate, a plurality of hoppers communicating with said channels and being provided with outlet openings, said outlet openings being provided with adjustable control gates.

In testimony whereof I affix my signature.
FALLIE COOK.
